CONNECTING PLUG AND CORD

Stanley A. Duvall, Edinburg, Tex., assignor to
Myrtle May Barker Duvall, Edinburg, Tex.

Application November 12, 1935, Serial No. 49,413

1 Claim. (Cl. 173—322)

This invention relates to electric iron fixtures and more particularly to an improved iron cord and electric connecting plug.

In ironing with the standard type of electric iron and cord the housewife has found it very inconvenient to have the iron cord dangling or resting on the ironing board, as the cord is continually in the way of the iron, ruffles the material being ironed and the user must constantly 10 keep moving the cord by hand from the path of the iron.

While many attempts have been made to overcome this inconvenience, they have never been as simple, practical and lasting as my device. For 15 example, heretofore, all such devices have relied on some separate bracket mounted on the ironing board, or iron in some instances, but in every such instance the arrangement has been proven to be very awkward and inconvenient. This is especially so because in all of these arrangements the cord interferes with the tilting of the iron back upon the iron rest, common to all standard 20 electric irons today. The old position of the iron cord not only hinders the use of the iron rest, but will not permit the use of a laterally extending rigid portion of the iron cord and also even if the rigid portion were made very short, which would be impractical, to permit the iron to be tilted on its rest, the result would be disastrous 25 as the insulation would be subjected to strain or shearing stress at certain points.

It is apparent therefore that an object of my invention is to overcome these defects by providing for a novel type of plug in combination with 30 a novel iron cord, which will not contact the ironing board or the material being ironed, or interfere with the use of the iron.

Another object of my invention is to do away 35 with the necessity of any outside supporting means for an iron cord to hold it above and out of contact with an ironing board.

And yet another object of my invention is to provide a strain relieving means at an extremity of the rigid section of the iron cord.

Other objects and advantages of my invention 45 will be disclosed in the following description and accompanying drawings, in which;

Figure 1 is a front elevation of my plug and iron cord, with a portion of the plug and cord cut away and in cross section.

Figure 2 is a bottom view of the plug and the rigid section of the cord.

Figure 3 is a fragmentary view in cross section 55 of the three sections which make up the cord

and shows how the mid-section may be bent upwardly or downwardly.

Figure 4 is a top view of an iron on an ironing board with my plug and cord connected for operation and showing how it may extend outwardly 5 from either side of the ironing board.

Figure 5 is a side view of an iron and ironing board and shows how readily the iron is tilted on its rest without interference from the cord.

Figure 6 is a rear view of an iron on an ironing 10 board showing the cord with its rigid first section above the ironing board and its pliable second strain reducing section bent upwardly.

Referring more particularly to the drawings, numeral 1 is an electric iron connecting plug of 15 any usual type of construction, preferably formed in two body sections A and B, so shaped as to form an upper enlarged head portion 2 to provide for a hand grip for connecting and disconnecting the same with an iron. The sections A and B of the plug head 2 are also cut to form openings 3 and 4 in each end of the said plug head.

A tube 5 extends from a point just outside the 20 plug head 2 longitudinally through the plug head 25 2 and the openings 3 and 4, and especial care is made to make a very tight fit of the tube in each of said openings. The tube 5 is beaded at 30 13 to act as a stop and is preferably made of aluminum or any other light material, it being 35 very desirable to have the entire assembly as light as possible so as to prevent any side movement of the plug and insure a solid connection between the plug contacts 14, which are made of greater length than the average, to enable 40 them to contact the entire length of the iron terminals, not shown. The portion of tube 5 which is inside the plug head 2 is slotted at 45 15 to permit the conductor wires 16 and 17 to extend downwardly therethrough for connection with the plug contacts 14. The elongated tube 5 extends outwardly from the plug and encloses the conductor cord 9 to make the said cord rigid along a section of its length as it leads out of the plug. The tube 5 is covered with an elongated textile covering 8, which covering 8 continues beyond the outer end 11 of the tube 5 for a short distance around and along the cord 9.

Beginning at the extremity of tube 8 and around the cord 9 is a pliable, tapering, spirally 50 wound piece of flat metal tape or wire 10, formed as a pigtail. This metal pigtail 10 is enclosed by the extended part of covering 8. The purpose of the pigtail 10 is to relieve strain at point 11 and prevent any shearing stress on the insulated 55

cord 9 and covering 8 by equalizing the strain along its length.

It should be noted at this stage of the description that the general appearance of the entire assemblage extending from the iron connecting plug is that of one continuous cable composed of three differently constructed sections. The first section (a) being rigid, the second (b) pliable, and the third (c) flexible. The distinction between the pliable and flexible sections being that the pliable section may be bent in any direction and will hold the form to which it is bent, while the flexible section will not retain a given form. This arrangement permits a freedom of swing and does not bind or pull.

As is shown in detail in Figure 3, the metal pigtail or the tapering spiral 10 permits the mid-section (b) to be bent in an arc in any direction desired and when so bent it will relieve the strain on the cable coverings at 11 which is the end of the rigid section (a) and tend to equalize the strain by placing a large part of it at the said arc. The remaining section (c) is merely the usual flexible cord, and it is held away and out of contact with the ironing surface of an ironing board by means of the rigid section and the pliable mid-section. The rigid section, constructed as hereinbefore described, may be of any length and extends substantially at right angles with the side of the iron along the line 6-6 of Figure 4, so as to extend to a point beyond the side of the ironing board or within a short distance thereof, when the pliable section or pigtail 10 is bent in the form of an arc either upwardly or downwardly. This obviously keeps the flexible portion of the ironing cord, the extreme end of which is connected to a power circuit plug, off of the ironing board and to the side of the ironing board so that the cord does not interfere at any time with the movement of the iron in any direction. If desired a button switch 12 may be formed in the plug head 2.

In operation the iron connecting plug is inserted in the socket of an electric iron so that the rigid portion extends transversely of the ironing

board and away from the ironer. (See Figure 4, general illustration.) If the ironer desires to iron on one side of the board in preference to the other, the plug may be turned around so that the rigid section extends transversely the ironing board, as on the line 6-6 of Figure 4, in the other direction. In any event the rigid section will hold the ironing cord above and out of contact with the material being ironed and away from the path of the iron. The mid-section, which is substantially a continuation of the rigid section, is bent either upwardly or downwardly in an arc so as to further assist in holding the flexible section away from the ironing surface and also to relieve strain as above explained. When a piece of material has been ironed the user may tilt the iron backward upon the iron rest as the cord with its rigid section extends from the plug at right angles with the side of the iron and not to the rear, therefore not interfering with the use of the iron rest which has been found so useful and is applied to all standard makes of irons. With this arrangement the ironer has no longer the inconvenience of the flexible iron cord which is constantly getting in the way of the iron and ruffling the goods and slowing up the work.

While I have shown and described my invention in one form, I wish it understood that I may use other constructions within the scope of the following claim.

What I claim is:—

In combination with an electric iron and an ironing board, a connecting plug and cord, including a suitable plug body with contacts mounted in the plug body and connected to a source of power by the cord, an elongated tube substantially half the length of the width of the ironing board extending at right angles from a side of the said plug, said cord extending from the plug contacts through the elongated tube, and a pliant cord holding member secured within the outer end of said tube and extending outwardly therefrom whereby to support the said cord above and out of contact with the ironing board.

STANLEY A. DUVALL. 45
